INSULATED WALL CONSTRUCTION

Arthur E. Small, Hammond, Ind., assignor to
 Standard Railway Equipment Manufacturing
 Company, Chicago, Ill., a corporation of Dela-
 ware

Application April 28, 1939, Serial No. 270,604

1 Claim. (Cl. 189—34)

My invention relates to insulated walls for use in connection with refrigerators or other insulated structures particularly relating to an insulated body for a railway car or automotive truck having an outside metallic sheathing and an inside lining of wood, Celotex, plywood or some similar material.

One of the objects of my improvement is to limit the heat transmission through the wall. In the past it has been customary in a wall comprising an outer metallic sheathing attached to metallic framing members to have the area of contact between sheathing and frame member relatively large. With my improved construction this contacting area is comparatively small thereby reducing the heat transmission through the wall due to the conductivity of the metallic parts.

Another object is to reduce the thickness of the wall.

In the drawing:

Fig. 1 shows a perspective view of a portion of a wall incorporating my invention.

Fig. 2 is a section taken on the line 2—2 in Fig. 1.

Figs. 3—5 inclusive show modified constructions.

My invention is adaptable to an insulated wall having an outside metallic sheathing 2 consisting of a plurality of sheets 3—4—5 with the side margins of adjacent sheets secured to each other. The metallic sheathing 2 is secured to a plurality of spaced apart posts 6—7. In the drawing I have shown the side margins of the adjacent sheets 3—4 and 4—5 overlapping and secured to the posts 6 and 7 respectively by means of rivets 8. This construction is not essential to my improvement as the sheet margins may be joined by welding in which case the joint 9 may be either lapped or butted nor is it necessary to have the sheet joint 9 positioned adjacent the posts.

In the past it has been common practice to secure the metallic sheathing of a wall to metallic posts having a relatively large flat surface contacting the sheets. In such a construction there is a relatively large transfer of heat from the sheathing 2 to the posts 6—7 or vice versa due to the large area of contact.

In my construction I reduce this heat transfer to a relatively small amount by providing the surface 10 of posts 6—7 adjacent the sheathing with ridges 12—16 respectively contacting the sheathing 2 and spacing said sheathing away from the surface 10 of the post. With my improvement I theoretically reduce the areas of contact between the sheathing 2 and the posts

6—7 from surface contacts to line contacts. I realize that in actual practice there will be some slight width of contact; however, the contacting area will be small as compared to the construction in common use with a correspondingly large reduction in the amount of heat transferred from the sheathing to the posts or vice versa.

The inside sheathing 13 is made of wood, plywood, Celotex, or masonite or some similar insulation material. To provide additional insulation value for the wall the space 14 defined by the posts 6—7, the outside metallic sheathing 2 and the inside sheathing 13 may be filled with an insulating material 15.

Fig. 3 shows a modified construction wherein the post 20 is provided with a convex surface 21 adjacent the metallic sheathing 22 to produce substantially a line contact between the post and the sheathing thus reducing the transfer of heat therebetween.

Fig. 4 shows a modified construction wherein spacers 30 separate the sheathing 31 from the post 32. The spacers 30 are of relatively small area thereby limiting the transfer of heat between the sheathing 31 and post 32.

Fig. 5 shows a modified construction wherein the post 40 is provided with outwardly embossed portions 41 contacting the sheathing 42. As the contacting area of an embossed portion 41 and the sheathing 42 is relatively small the heat transfer therebetween will be small.

In the drawing I have shown U shaped posts. However, it is to be understood that posts of any suitable section provided with my improvement may be used.

The accompanying drawing illustrates the preferred form of the invention, though it is to be understood that the invention is not limited to the exact details of construction shown and described, as it is obvious that various modifications thereof, within the scope of the claim, will occur to persons skilled in the art.

I claim:

In a wall for a refrigerator, a substantially channel-shaped post comprising a web and spaced apart flanges, an outwardly projecting corrugation in said web extending the length of said post, metallic sheathing secured by spaced apart rivets to said corrugation in spaced relation to the uncorrugated parts of said web, outwardly extending reflanges on said flanges, wooden lining disposed in flatwise relation with said reflanges and in spaced relation to said sheathing, and insulation between said sheathing and said lining adjacent said post.

ARTHUR E. SMALL.
